GOLF SHOE CLEAT CLEANER

Joseph L. Racina, 7315 W. 62nd Place, Argo, Ill.

Filed Apr. 7, 1960, Ser. No. 60,080

Term of patent 14 years

(Cl. D9—2)

I claim:

The ornamental design for a golf shoe cleat cleaner, substantially as shown.
